UNITED STATES PATENT OFFICE.

HUGH W. MATTHEWS, OF BALTIMORE, MARYLAND.

CORN AND CANE HARVESTER.

SPECIFICATION forming part of Letters Patent No. 351,877, dated November 2, 1886.

Application filed December 12, 1885. Serial No. 185,519. (No model.)

To all whom it may concern:

Be it known that I, HUGH W. MATTHEWS, of Baltimore, in the State of Maryland, have invented a new and useful Improvement in 5 Corn and Cane Harvesters, of which the following is a full, clear, and exact description, reference being had to the accompanying drawings, making part of this specification.

My invention relates to certain improvements in the construction of the cutting apparatus, reel, and dropper, and in the arrangement of the cut-off, operating in connection with the dropper, and will be fully understood from the following description and claims.

15 In the accompanying drawings, Figure 1 represents a side elevation of my improved machine, with the outer fender or side of the stalk-platform or dropper-tray and the adjacent dropper removed or broken away to show other parts, the position of the fender being indicated by dotted outline in part. Fig. 2 is a front elevation of the machine, with the points of the fenders or outer sides of the dropper-trays broken away; and Fig. 3 is a plan view 20 of the machine, with portions removed to show other parts, and showing in dotted lines the position the cut-off rods assume when the tray is dumped. Fig. 4 is a perspective view of one of the reels enlarged, showing the means 25 for effecting certain adjustments thereof. Fig. 5 is a side elevation of the cut-off of one of the dumping-trays, and certain parts with which it is connected for supporting and operating it; and Fig. 6 is a perspective view of one of 30 the knife guards or fingers and a portion of the finger-bar.

The machine, in its organization or general construction and arrangement of parts, is similar to that described in Reissued Letters Patent No. 10,601, granted to me May 26, 1885, and will therefore be described in detail only so far as is necessary to an understanding of the improvements herein claimed. A stout rectangular main frame (indicated at A) is arranged between the main driving and carrying wheels B and B', and supported at a suitable height above the ground upon standards A', in which the drive-wheel axle B' is journaled, said axle carrying a bevel-gear, B'', from 45 which motion is communicated to the band-cutters.

To the forward end of the frame A is secured

one or more pendent bars or hangers, C, preferably two, as shown, one at each front corner; and to the lower ends of these the finger-bar D is rigidly secured, said bar extending across under the front end of the main frame and in front of the driving-wheels and projecting laterally on both sides thereof, as shown. The projecting ends of this bar are provided with suitable guards or fingers, d, preferably of a construction and secured to the bar D in a manner hereinafter described, and upon each side of each of the two series of fingers thus located, and in suitable bearing-brackets secured to the bar D, are journaled rollers or drums e e' and e'' e'', arranged in pairs, with a set of fingers, d, between each pair. The drums or rollers are by preference provided each with a peripheral groove adapted to receive 70 and guide an endless band-cutter, f or f', one for each pair of drums, and the band-cutters, which are made each from a single strip of thin elastic steel with its forward edge brought to a knife-edge and serrated, are stretched tightly 75 thereon. The inner and adjacent rollers, e' and e'', are provided each with a sprocket-wheel, e', from which driving-chains g extend to driving sprocket-wheels G' and G'' on the forward end of a centrally-arranged longitudinal shaft, G, which is geared in any suitable manner to and operated from the bevel-wheel B' on the main drive-wheel axle.

The guards or fingers d may be of any suitable form, that preferred being shown in the 85 enlarged detail view, Fig. 6, consisting, in the main, of a plate or bar flanged on its upper and lower edges, tapering to a point at its forward end, and provided at its rear end with an inclined transverse flange or foot, d', through 90 which it is bolted or otherwise firmly secured to the forward face of the finger-bar D. It is provided on its upper and lower faces or flanged edges with keepers d' d'', or loop-guide brackets, through which the endless band-cutter 95 passes, and which serve to guide said band and to prevent its being deflected from its proper path by the pressure of the stalks against its forward cutting-edge in the forward movement of the machine.

100 Each guard or finger d is provided with a curved or angular rod, d'', secured through a foot, d', or otherwise, to the finger at or near its forward end or point, and extending thence

upward and backward above the plane of the upper face of the finger to a point in rear of the line or vertical plane of the cutting edge of the knife in such manner as to serve to uphold the stalks of corn against lateral deflection by the action of the cutter, and to guide the same backward for causing them to fall properly on the receiving tray or platform.

The finger-bar is made preferably of iron in the angular form (in section) indicated in Fig. 6—that is to say, having an upright portion set inclining forward for facilitating its passage over the stubble and other obstructions—and provided at its upper and lower edges with rearwardly-projecting flanges, between which may be secured a bar of wood, D', if desired, for stiffening the bar D and facilitating the attachment thereto of other parts of the machine.

H indicates a transverse shaft mounted in suitable bearings on the forward end of the main frame, and to which motion is communicated from the main drive-wheel axle through suitable sprocket-wheels and an endless driving-chain, (indicated in the drawings and described in my former patent, referred to,) the shaft H being also provided with bevel-gears H' and H², engaging and driving similar gears or pinions, H³, on the lower ends of upright reel-shafts I and I'.

The reel-shafts are journaled in upright sleeve-standards J and J', having arms j, which project laterally from near their lower ends, and are curved downward outside of the gears connecting the reel-shafts with the shaft H, and have eyes or short sleeves on their lower ends, through which they are pivoted on the ends of said shaft H. The sleeves J and J' have a rod, h, connecting their upper ends, said rods being divided preferably at two or more points, the adjacent ends thereof being provided one with a right and the other with a left hand screw-thread, and are coupled or united by means of a similarly-threaded sleeve or elongated nut, h', by means of which the reel-shafts and their supporting sleeves may be adjusted on the shaft H, for bringing the gears H³ snugly into mesh with the gears H' and H². At or near the center of its length the shaft H has a standard, h², pivoted upon it through a sleeve, h³, at its lower end, and provided at its upper end with a similar sleeve, h⁴, which surrounds the rod h, connecting the reel-standard sleeves, and serves to materially stiffen said rod, and thereby to assist in properly upholding the reels.

The rod h has the forward bifurcated end of a link or rod, i, connected with it, the rear end of said link being connected to an upright hand-lever, i', arranged within reach of the driver in his seat on the machine, and by the adjustment of which the reel-standard may be rocked on the shaft H, for moving the reel forward or back, as desired, the lever having the usual or any suitable form of thumb-lever, latch, and rack for holding it at the desired adjustment. The reel-standard sleeves have

curved arms j', formed on or secured rigidly to their upper ends on the outer sides thereof, which terminate each in an upright or standard, j², to which is adjustably secured a pendulum arm, formed on a cam-ring, K, surrounding the upper end of the reel-shaft. The arm k has a series of perforations in it, through any one of which a bolt or set-screw, k', passes into or through the standard j², for setting the cam-ring at the desired height. To the shaft I and I' is secured an adjustable head or disk, I², having a hub or sleeve on its lower side, through which a pin or set-screw, i², passes into the reel-shaft for holding the head at any desired height thereon corresponding to the adjustment of the cam-ring K, the shaft having a series of sockets or holes to receive the pin or screw i², as shown.

The upper face of the disk I² has a series of vertical ribs, l l', formed upon it, arranged in pairs, to form a series of sockets tangential to a circle outside of but concentric with the reel-shaft, in which sockets reel-arms L, L', and L² are secured by means of pivot pins or bolts l' passing through the ribs and through the heel ends of the reel-arms. These arms extend outward over the cam-ring K, which is set in an inclined position, with its highest side or portion on the side adjacent to the main frame, and the arms resting thereon are guided and upheld in such manner as to pass in substantially a horizontal position over the cutting apparatus for reeling the stalks in thereto and causing them to be deposited behind the same, after which, owing to the form of the cam, said arms are rocked upward on their pivots to pass over the frame and its attachments, and to pass the similarly-actuated arms of the other reel in a manner that will be readily understood. By the adjustments of the reels and their cams, as described, the reels can be readily adapted to the condition of the stalks to be operated upon.

The bundle-dumping trays or droppers are constructed substantially as described in my former patent, referred to—that is to say, each flooring N N' of two parts, connected at the sides with inclined rock-shafts M and M', which are geared together and connected with a single hand or foot lever, enabling the attendant to operate them simultaneously, as explained in said patent; but this two-part flooring, instead of extending to the finger-bar, as in said patent, is shortened in front, and the ends thereof may be beveled or rounded off, as shown at n n', Fig. 3, to permit the interpolation between said ends and the finger-bar D of a board, N², rounded or V-shaped on its rear edge, extending the whole width of the dumping-tray, and hinged at its forward edge to the finger-bar for permitting its rear edge to be raised and lowered with the sides of the tray. The rock-shafts M' or M and M', either or both, are provided with lever-arms m, extending laterally outward and upward, and cords or chains m' extend thence to the rear edge of the boards N², and are connected therewith,

the arrangement being such that when the boards N and N' are rocked downward to dump their load, the board N², on which the butt-ends of the stalks rest, will also be rocked downward, facilitating the discharge of the load, and will be correspondingly raised when the sides are raised to receive another load. By this arrangement the forward depressed ends of the inclined sides N and N' are removed back of the finger-bar far enough to adapt them to be freely swung down in dumping the load without endangering their striking and being injured by obstructions, and the beveling or rounding of the ends, as shown and described, tends to further relieve them from such danger and to facilitate their passage over obstructions, if they should meet any. The board N², when depressed, will of course swing up freely on its hinge to pass over any obstructions in its path.

The rock-shafts M and M' are provided near their forward ends with a short arm or perforated lug, p, on their upper or inner sides, from which links p' extend upward and outward, passing through the slatted side frames or fenders, Q, of the dropper-tray, their upper ends being connected to the outer ends, or heel-extension beyond their pivots, of cut-off rods or bars P and P', pivoted in suitable brackets, q, secured to the upper longitudinal bars, Q', of the slatted fenders Q. The bars or rods P and P' are of sufficient length to cause the ends thereof, when they are raised into a horizontal or nearly horizontal position, to lap by each other, as indicated by dotted lines in Fig. 3, and they are raised into this position to adapt them to catch and hold the falling stalks whenever the rock-shafts M and M' are rocked for causing the dumping-tray to discharge its load, and serve to uphold the stalks in an inclined standing position until the dumping-tray, after discharging its load, is returned to position to receive a new load, the cut-off rods P and P', simultaneously with such return of the dumping-tray, being allowed to swing down against the sides of the tray, depositing their load in the latter in a manner that will be readily understood.

The means for supporting the dumping-trays are substantially the same as in my former patent, referred to, and need not be herein described.

In the arrangement of the endless band-cutter described the stalks will be severed at two points—one above and the other below the guards or fingers d—and only the upper and valuable portion will of course be saved; but the heavy chopping action incident to the use of the scalloped cutter in common use, whether in a reciprocating or endless-chain form, is avoided, and the cutting action is steady and uniform, equalizing or evenly distributing the expenditure of power required to operate the cutters, and making the machine much more steady in operation.

Parts of the machine shown in the drawings, and not specifically hereinabove described,

will be constructed and arranged substantially as described in my former patent referred to.

Having now described my invention, I claim as new—

1. In a corn and cane harvesting machine, an endless band-cutter having a straight or continuous serrated cutting-edge, in combination with fingers provided each with an independent guide for said band cutter, substantially as described.

2. The combination, in a corn and cane harvester, of the fingers provided each with independent guides on their upper and lower sides or faces, and an endless band-cutter passing around said fingers and through said guides, substantially as described.

3. In a corn and cane harvester, the two endless band-cutters arranged to project on opposite sides of and to be operated from a single central driving-shaft, in combination with the fingers provided each with a guide for said endless cutters, substantially as and for the purpose described.

4. In a corn-harvester, the combination, with the guards or fingers provided with an independent guide, of a continuously-moving endless band-cutter and curved rods or fingers arranged to overhang the cutting-edge of said band-cutter for supporting the stalks against lateral deflection, substantially as described.

5. The upright reel-shafts provided with the adjustable disks having the vertical ribs on their upper faces arranged in pairs and forming, in connection with the disk to which they are applied, open-top sockets for the reel-arms, in combination with the reel-arms pivoted in said sockets, and the adjustable cams, all arranged and operating substantially as described.

6. The upright tubular reel-shaft standards pivoted on a shaft actuating the reel-shafts, in combination with the divided rod connecting said standards and the threaded sleeves for uniting and adjusting the parts of said divided rod, substantially as described.

7. The combination of the upright reel-standards, the dividing-rod connecting said standards, means, substantially as described, for adjusting, and the intermediate standard for supporting, said connecting-rod, substantially as described.

8. The combination of the reel-actuating shaft, the reel-standards pivoted thereon, the divided rod connecting said standards, the intermediate supporting-standard for said rod, and the adjusting-lever connected to said rod for adjusting the reels, substantially as described.

9. The dropper or dumping tray provided with the longitudinally-pivoted parts or sides N N', and the transversely-pivoted part or board located in front of the parts or sides N and N', substantially as described.

10. The dropper composed of the longitudinally-hinged sides N and N', and the transversely-hinged board N², in front of said sides, in combination with the longitudinal rock-

shaft provided with a lever-arm, and a flexible connection between said arm and the hinged dropper section or board N^o , substantially as described.

5 11. The pivoted sides N and N' of the dumping tray bottom or flooring, provided with the rounded or beveled forward ends, in combination with the transverse V-shaped portion of said tray arranged in front of said sides, substantially as and for the purpose described.

12. The combination, with the longitudinally-divided dumping-tray, of the divided cut-off, consisting of the rods P and P' , arranged at or near the front, above and on opposite sides of the divided tray and pivoted to the side fenders thereof, and connections between said rods and the tray-sections, whereby said parts are operated simultaneously in such manner that as the sections of the tray 15 are dropped the cut-off rods will be raised to support the falling stalks in an inclined standing position, substantially as described.

13. The divided dumping-tray, having the longitudinal side shafts provided with lugs or

arms p p , in combination with the divided cut-off, consisting of pivoted rods P and P' , arranged near the forward end of and above said dumping-tray, and connections between said cut-off rods and the arms p p , whereby, when the tray-sections are dropped to discharge their load, the cut-off rods will be raised to catch and uphold the falling stalks in an inclined standing position until the tray is again raised, substantially as described.

14. The combination, in a corn and cane harvester, of the dumping-tray having its flooring composed of side sections connected to longitudinal rock-shafts, and a hinged transverse section connected with and operated from the longitudinal shaft of a side section, substantially as described.

In testimony whereof I have hereunto set my hand this 9th day of December, A. D. 1885.

HUGH W. MATTHEWS.
